UNITED STATES PATENT OFFICE.

PRESTON V. BURSON, OF BROADWAY, OHIO.

ROAD-WORKING MACHINE.

1,069,524.

Specification of Letters Patent.

Patented Aug. 5, 1913.

Application filed November 5, 1912. Serial No. 729,637.

To all whom it may concern:

Be it known that I, PRESTON V. BURSON, a citizen of the United States, residing at Broadway, in the county of Union and State 5 of Ohio, have invented new and useful Improvements in Road-Working Machines, of which the following is a specification.

This invention relates to road working machines, and it has for its object to produce a road scraping, grading and leveling 10 machine of simple and improved construction.

A further object of the invention is to produce a machine of the class described in 15 which the frame structure will be supported and balanced on a wheel carrying axle, means being provided whereby the frame structure may be conveniently lowered into position for operation or elevated for trans- 20 portation.

A further object of the invention is to produce a simple and improved construction whereby the scrapers may be readily tilted or adjusted to crown the road that is being 25 operated upon at the desired angle or pitch.

A further object of the invention is to combine with the machine a spreader and means whereby said spreader may be conveniently adjusted.

30 A further object of the invention is to provide simple and effective tilting or adjusting means operating in connection with the tongue or draft member and whereby the machine may be readily adjusted to and 35 maintained in a level condition.

With these and other ends in view which will readily appear as the nature of the invention is better understood, the same consists in the improved construction and novel 40 arrangement and combination of parts which will be hereinafter fully described and particularly pointed out in the claims.

In the accompanying drawings has been 45 illustrated a simple and preferred form of the invention, it being, however, understood that no limitation is necessarily made to the precise structural details therein exhibited, but that changes, alterations and modifications within the scope of the claims may be 50 resorted to when desired.

In the accompanying drawings, Figure 1 is a top plan view of a machine constructed in accordance with the invention, said machine being shown with a tongue

truck. Fig. 2 is a side elevation, the tongue 55 truck having been detached and the machine being shown in operative position. Fig. 3 is a longitudinal sectional view, enlarged, taken on the line 3—3 in Fig. 1, the frame being raised for transportation. Fig. 4 is 60 a transverse sectional view, enlarged, taken on the line 4—4 in Fig. 1. Fig. 5 is a front elevation. Fig. 6 is a perspective detail view of the crown lever and related parts. Fig. 7 is a perspective detail view of the 65 tilting lever and related parts. Fig. 8 is a sectional detail view taken on the line 8—8 in Fig. 1.

Corresponding parts in the several figures are denoted by like characters of reference. 70

The axle 1 of the improved machine is equipped with transporting wheels 2, 2. The sills or frame bars 3, 3 which extend longitudinally beneath the axle and which are suitably spaced and connected by means of 75 blocks 4 are supported adjustably by a compound lever including a member 5 which is fulcrumed on the axle with which it is connected by means of a clip 6. A second lever 7 is fulcrumed on a link 8, whereby it 80 is suspended from the long arm of the lever 5. The short arms of the levers 5 and 7 are connected with the sills or frame bars by means of links 9, 10 which are located, respectively, in front and in rear of the axle. 85 It will be seen that by manipulating the long arm of the lever 7, the sills or frame bars may be lowered, as seen in Fig. 2, or raised to the position indicated in Fig. 3.

A platform 11 supported on the rear ends 90 of the sills has an upright 12 with which the long arm of the lever 7 may be adjustably connected by means of a pin or bolt 13 engaging one of a plurality of apertures 14 in the upright, thereby permitting the 95 sills or frame bars to be supported at various adjustments. It is also evident that by means of the compound lever arranged as described, the sills or frame bars even when of great weight will not require the 100 services of more than one man for the purpose of raising or lowering the same. It may be here stated that the sills, as well as other parts of the machine, may be made of timbers of suitable dimensions to insure 105 the requisite strength and weight for successful operation, or the machine may be constructed mainly of metal, such as steel.

in which event channel bars and angle bars of well known and convenient form will be preferably chosen.

The spreaders 15 are connected at their inner ends with the sills or frame bars 3, 3 from which they extend outwardly, as shown. The inner ends of the spreader bars are positioned adjacent to the under faces of the sills with which they may be connected by means of bolts 16 that act as pivots upon which the spreaders may be adjusted to various angles with respect to the sills. For the passage of the bolts 16, the spreader bars are provided with bores 17 which may be made slightly flaring, as seen in Fig. 8, but which in any event are made sufficiently large to enable the spreader bars to be tilted or dipped with respect to the sills to a suitable position for crowning a road, as will be clearly seen in Figs. 4 and 5 of the drawings, it being understood that for grading or leveling the spreader bars may be adjusted to an approximately horizontal position. The spreader bars 15 at each side of the machine 25 are joined together by a longitudinal connecting bar 18, each of said connecting bars being connected with the spreaders at one side of the machine by bolts or pivot members 19. A cross bar 20 supported on the 30 sills adjacent to the front ends thereof is connected with the bars 18 by means of links 21, said links being adjustably connected with the bars 18 by bolts or fastening members 22 for the reception of which each of 35 the bars 18 is provided with a plurality of apertures 23, thereby enabling the angles of the spreaders with respect to the sills to be varied.

24 is a cross bar extending transversely 40 across the sills and provided at the ends thereof with knees 25 that are loosely supported on the connecting bars 18. The knees or knee blocks 25 may be slidably and adjustably connected with the crown bar 24 in 45 order to adapt themselves to various adjustments of the bars 18 caused by adjustment of the spreaders to various angles. The knee blocks are flexibly connected with the bars 18 by means of links 26. Fulcrumed on one 50 of the sills 3 is a bell crank having a short arm 27 which is suitably connected with the crown bar 24. This connection, as seen in Fig. 6, may be brought about by mounting on the crown bar a recessed block or casting 55 28 having a pin 29 engaging a slot 30 in the lever arm 27. The bell crank also has an upwardly extending arm constituting a handle 31, whereby it may be manipulated, said handle being provided with a conventional 60 stop member 32 engaging a rack segment 33, whereby the lever and related parts may be retained at various adjustments. It will be seen that by manipulating the bell crank the 65 distance between the crown bar 24 and the sills 3 may be varied. The crown bar is sup-

ported by the knees 25 which loosely engage the connecting bars 18 near the outer ends of the spreaders 15. By manipulating the bell crank to lift the sills, the inner ends of the spreaders which are connected with the 70 sills by the bolts 16 will be lifted or tilted in an upward direction, as seen in Fig. 4, so that the road surface operated upon will be crowned to an extent regulated by the relative adjustment of the sills and the crown 75 bar.

A tongue 34 which has been shown as being of the split or bifurcated type is connected pivotally at its rear end with the sills 3 by means of a pin or bolt 35. The forward 80 end of the tongue may be supported on a tongue truck C, as indicated in Fig. 1 of the drawings, or it may be supported by means of an ordinary neck yoke from the necks of the team; again, when a traction engine is 85 employed, the front end of the tongue may be pivotally connected with the engine frame of truck and in this manner supported, and it may be stated that when a traction engine is used, the length of the tongue may 90 be considerably reduced. When the tongue truck C is employed, the draft animals may be attached to said truck by means of an evener D; when the tongue truck is not employed, the team may be hitched to an evener 95 36 suitably connected with the frame structure of the machine. The forward end of the frame structure is adjustably connected with the tongue by means of a bell crank 100 fulcrumed at 37 on the sills, said bell crank having a short arm 38 which is connected by a link 39 with the rear end of the tongue, and said bell crank having also an upwardly extending arm constituting a handle 40 which is equipped with the conventional 105 stop member 41 engaging a rack segment 42, whereby the bell crank and associated parts may be retained at various adjustments.

A V-shaped scraper 43 is provided, said scraper being connected by means of link 110 bars 44 with the foremost spreaders 15, provision being made whereby the links 44 may be adjustably connected with the said spreaders. For the purpose of effecting vertical adjustment of the scraper a lever 45 is provided, said lever being fulcrumed at 46 on the tongue 34, and said lever being connected with the scraper by means of a link 47. An upright 48 rising from the sill frame is provided with an adjustable pin or bolt 49, 120 whereby the lever 45 may be retained at various adjustments.

From the foregoing description, taken in connection with the drawings hereto annexed, the operation and advantages of this 125 invention will be readily understood by those skilled in the art to which it appertains. When the machine is raised for transportation, as seen in Fig. 3 of the drawings, the frame structure will be bal- 130

anced on the axle, and will be also maintained by the bell crank whereby it is connected with the tongue in a constant approximately horizontal position, avoiding any jerking and oscillatory movement of the frame as the machine is carried along over the road. By manipulating the lever 7, the frame may be lowered toward the ground, after which the lever arm 41 may be manipulated to effect a proper adjustment of the frame with respect to the tongue, whereby the frame will again be maintained in an approximately horizontal position. By manipulating the lever arm 31, the spreaders may be adjusted to crown the surface of the road to the desired pitch, and the scraper 43 may be adjusted in advance of the spreaders by means of the lever 45. Thus, by proper adjustment of the parts the center portion of the road may be scraped, and the material thus loosened will be deflected and spread in an upward and inward direction by the spreader bars, thus leaving the road in good condition for subsequent travel and to shed water. Various other uses of the machine will readily suggest themselves, and the range of utility of the improved machine will be found to be very expensive. When the machine is made mainly of wood, the various parts may be reinforced, and the scraper and spreaders may be provided with steel blades, as indicated in the drawings at 50. It is obvious that joints and connecting members of well known construction may be employed in place of those herein shown and illustrated to enable the parts to be adjusted and manipulated in the manner herein set forth. The improved machine is simple in construction, is capable of being produced at a moderate cost, and it has proven in actual practice to be thoroughly efficient for the purposes for which it is provided.

Having thus described the invention, what is claimed as new, is—

1. In a road working machine, a wheel carrying axle, a frame including longitudinal sills extending beneath the axle, means for supporting and vertically adjusting the frame with respect to the axle, a tongue connected pivotally with the frame, means for supporting the front end of the tongue, means for securing the tongue with respect to the frame and for varying the angle therebetween, outwardly extending spreaders connected flexibly with the sills, bars connecting the spreaders in series at the two sides of the machine, and means for vertically adjusting the sills with respect to the outer ends of the spreaders to tilt the inner ends of the latter in an upward direction.

2. In a road working machine, a frame including longitudinal sills, a plurality of spreaders positioned beneath and extending

outwardly from and flexibly connected with each of the sills, bars connecting the spreaders in series at the two sides of the frame, a crown bar extending across the sills and having knees engaging the connecting bars, links connecting the knees with the connecting bar, and means including a bell crank lever for adjusting and supporting the crown bar with respect to the sills. 70

3. In a road working machine, an axle 75 having transporting wheels, a frame including longitudinal sills extending beneath the axle, and means whereby said sills are connected and spaced apart, means for vertically adjusting and supporting the frame 80 with respect to the axle, a tongue connected pivotally with the frame, means for varying the angle of the tongue with respect to the frame, outwardly extending spreaders connected flexibly with the sills, bars connecting the spreaders in series at the two sides of the machine, a crown bar extending across the sills and having knees supported on the bars connecting the spreaders, links connecting the knees with said bars, and 85 means for varying the distance between the crown bar and sills and for securing the same at various adjustments. 90

4. In a road working machine, a frame including longitudinal sills, and means 95 whereby said sills are connected and spaced apart, outwardly extending spreaders connected flexibly with the sills, bars connecting the spreaders in series at the two sides of the frame, said bars being positioned at 100 a distance from the outer extremities of the spreaders, a crown bar having knees supported loosely on the connecting bars, links connecting the knees with the connecting bars to permit the latter to have a limited 105 rocking movement, and means for lifting the sills with respect to the crown bar to tilt the inner ends of the spreaders upwardly while said spreaders are supported on their outer extremities. 110

5. In a road working machine, a frame including longitudinal sills, outwardly extending spreaders flexibly connected with the sills, means for tilting the spreaders to elevate the inner ends thereof while said 115 spreaders are supported by their extremities engaging the ground, a scraper supported forwardly of the spreaders, and means for effecting vertical adjustment of the scraper.

6. In a road working machine, a wheel carrying axle, a frame including longitudinal sills extending beneath the axle, means for supporting and adjusting the frame with respect to the axle, spreaders connected flexibly with and extending outwardly from the sills, bars connecting the spreaders in series, means for securing the spreaders with respect to the sills and for varying the angle therebetween, a crown bar extending across the sills and having knees supported on and 125 130

connected flexibly with the bars connecting the spreaders, said knees being slidably connected with the crown bar, and means including a bell crank for varying the distance between the crown bar and the sills and for securing the parts at various adjustments.

In testimony whereof I affix my signature in presence of two witnesses.

PRESTON V. BURSON.
